UNITED STATES PATENT OFFICE.

OSCAR R. GLEASON, OF NEW YORK, N. Y.

BRIDLE-BIT.

SPECIFICATION forming part of Letters Patent No. 378,305, dated February 21, 1888.

Application filed December 12, 1887. Serial No. 257,703. (No model.)

To all whom it may concern:

Be it known that I, OSCAR R. GLEASON, of New York, in the county of New York and State of New York, have invented a new and useful Improvement in Bridle-Bits, of which the following is a specification.

The invention consists of a bridle-bit having its mouth-piece approximately square in cross-section and provided with rings having downwardly-projecting arms and upwardly-projecting loops, all as hereinafter fully described.

Figure 1 is a plan view of my improved bit, partly in section. Fig. 2 is a cross-section on the line $x-x$. Fig. 3 shows a riding-bridle having my improvement applied and arranged for gentle horses, and Fig. 4 shows a bridle arranged for vicious horses.

Similar letters of reference indicate corresponding parts in all the figures.

Referring to the drawings by letter, A represents the mouth-piece or bit proper, which is made square in cross-section, with its edges cut off or dulled to prevent injury to the horse's mouth. To each end of the mouth-piece or bit proper are attached the rings B, in the usual manner. The rings B, preferably made of steel and cast in one piece, are each formed with the downwardly-projecting arm b , having a slot, b^2 , for attaching the reins, and with the upwardly-projecting loop or eye b^3 for receiving a curb-strap when desired.

For ordinary use the headstall C and reins D will both be secured to the rings B, as shown in Fig. 3; but when the bit is to be used upon vicious and unruly horses the reins D are secured to the arms b , and a curb-strap, E, which passes under the jaw of the horse, is secured to the loops or eyes b^3 , as shown in Fig. 4. When thus arranged, by pulling on the reins, the leverage being increased, the mouth-piece or bit proper will be turned, and owing to its being square it will be impossible for the horse to take the bit in his teeth and hold on to it. Instead of forming the arms b of the rings with slots, rings may be secured to the ends thereof, 45 as in the ordinary manner.

Having thus described my invention, what I claim, and desire to secure by Letters Patent, is—

An improved bridle-bit consisting of the 50 mouth-piece A, square in cross section, and the rings B, provided with the downwardly-projecting arms b and the upwardly-projecting loops or eyes b^3 , substantially as herein shown and described.

OSCAR R. GLEASON.
